(57) CLAIM

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken lines immediately adjacent to the shaded area, including the broken lines forming six circular regions surrounded by the shaded area, represent unclaimed boundaries of the design. The broken lines within the shaded area and the broken lines showing the remainder of the shoe upper are for environmental purposes only and form no part of the claimed design.
